(57) **CLAIM**

The ornamental design for a guide rail support bracket assembly, as shown and described.

DESCRIPTION

FIG. 1 is a perspective view of my design for a guide rail support bracket assembly;

FIG. 2 is a front view thereof;

FIG. 3 is a back view thereof;

FIG. 4 is a right side view thereof;

FIG. 5 is a top view thereof;

FIG. 6 is a left side view thereof; and,

FIG. 7 is a bottom view thereof.

The broken lines in FIG. 3 represent a portion of the guide rail support bracket assembly that forms no part of the claimed design.

1 Claim, 3 Drawing Sheets
